(57) CLAIM

The ornamental design for a faux turf tree skirt, as shown and described.

DESCRIPTION

FIG. 1 is a perspective view of a faux turf tree skirt, showing my new design in a used condition with a tree shown in broken lines;

FIG. 2 is a top plan view thereof;

FIG. 3 is a bottom plan view thereof; and,

FIG. 4 is a side view thereof.

All surfaces not shown form no part of the claimed design. The broken lines in FIG. 1 that indicate an image of a Christmas tree are included for the purpose of illustrating the faux turf tree skirt in a state of use and form no part of the claimed design.
